CARBONATED BEVERAGE DISPENSING VALVE

Le Roy D. Gore, Theodore L. Hanson, and Donald W. McBride, Kansas City, Mo., assignors to The Vendo Company, Kansas City, Mo., a corporation of Missouri

Application April 18, 1956, Serial No. 579,010

2 Claims. (Cl. 251—54)

This invention relates to valve structure especially adapted for use in the dispensing of carbonated beverage drinks especially where the proper proportions of carbon dioxide, water, and syrup are pre-mixed and directed to the valve structure in such condition.

In the dispensing of beverages containing carbon dioxide, there is presented the problem of maintaining such ingredient of the drink in solution. Manifestly, the nature of CO₂ is such that it commences to dissipate immediately to the atmosphere when discharged from a sealed container therefor and such release from the solution is enhanced whenever the drink is dispensed at high velocities as well as when the beverage is agitated to such extent as to cause foaming during the manipulation of the valve structure.

It is accordingly, the most important object of the present invention to provide valve structure wherein the aforesaid agitation due to operation of the valve structure itself is kept at a minimum and to provide additionally, novel components capable of reducing the pressure within the valve structure itself sufficiently to permit low velocity dispensing of the beverage when the valve is moved to an open position.

Another important object of the present invention is the provision of valve structure having a restrictor as a part thereof and contained within the valve body in such manner as to present an elongated, annular space through which the beverage must flow from the inlet of the valve structure to the outlet thereof, thereby reducing the pressure thereof and permitting lower velocity dispensing of the drink.

A further object of the instant invention is to reduce agitation during the manipulation of the valve to the open position by the inclusion of damping means rendering it impossible to quickly and violently shift the valve to the open position.

A still further object of the instant invention is the provision of valve structure of the aforementioned character wherein the damping means just above mentioned is in the nature of a piston forming an integral part of the valve itself and extending into an air chamber that is contained within the elongated restrictor carried by the valve body.

Another important object of the instant invention is the provision of valve structure having the various parts thereof formed and arranged as to permit quick and easy removal, thereby facilitating cleaning operations.

Other objects include important details of construction to be made clear as the following specification progresses.

In the drawing:

Figure 1 is a longitudinal, substantially central, cross-sectional view through a carbonated beverage dispensing valve made according to the present invention, showing the same operably associated with the machine with which it is adapted to be used;

Fig. 2 is a transverse, cross-sectional view taken on line II—II of Fig. 1; and

2

Fig. 3 is a transverse, cross-sectional view taken on line III—III of Fig. 1.

As above indicated, the beverage to be dispensed through the medium of the valve about to be described is in the nature of a "pre-mix" containing the proper proportions of CO₂, water and syrup, such mixture being stored within the machine in a container 10. It is contemplated that the temperature of the beverage be lowered through use of a flash cooler 12 within which the container 10 is disposed, but the details of construction of such cooler form no part of the instant invention and, therefore, have not been disclosed.

The valve structure forming the subject matter of the instant invention includes a body 14 in the nature of an elongated tube or sleeve traversing one wall of the flash cooler 12 and held in place by a fastener 16 cooperating with a shoulder 18 at the opposite end of the body 14. A centrally perforated plug 20 presenting an inlet 22 is releasably held in place within one end of the body 14 by a snap ring 24 and an O-ring 26 carried by the plug 20 seals the body 14 against escape of liquid at the innermost end of the body 14. Plug 20 may be placed in communication with the container 10 in any suitable manner as through use of a flexible tube 28.

A head 30 provided with a longitudinal bore 32 extends into the outermost end of the tubular body 14 and is provided with an O-ring seal 34. Head 30 is releasably held in place within the body 14 through the medium of a U-shaped key 36 embracing the body 14, the legs of the key 36 extending into opposed slots formed in the body 14, one of which can be seen in Fig. 2 and designated by the numeral 38. The said legs of the key 36 are received by an annular groove 40 formed in the head 30.

Head 30 is provided with a laterally extending outlet orifice 42 communicating with the bore 32 thereof and releasably receiving an elongated tubular spigot 44 that is held in place by a spring-loaded, bifurcated retainer 46 yieldably biased against shoulder 48 formed on the spigot 44.

A guide 50 for spring 52 surrounds a plunger 54 between spring 52 and a removable cross pin 56 that traverses the plunger 54. Spring 52 is coiled about the plunger 54 and about the proximal end of the head 30 to not only yieldably bias the plunger 54, toward the outermost end of its path of travel, but yieldably hold the retainer 46 in place engaging the shoulder 48 of spigot 44, it being understood that the retainer 46 is shiftable with respect to the head 30 toward and away from the guide 50.

Plunger 54 is reciprocable within the bore 32 and is provided with a reduced portion 58 adjacent the lateral discharge 42.

A piston 60 integral with the plunger 54 carries a valve in the nature of a washer 62 adjacent the reduced portion 58 of plunger 54 which is yieldably held biased against a seat 64 formed in the innermost end of head 30 by spring 52.

Piston 60 extends into an air chamber 66 formed in an elongated restrictor 68 and sealed by an O-ring 70 that circumscribes the piston 60 at the innermost end of the latter.

Restrictor 68 is loosely mounted within the valve body 14 for free reciprocable movement longitudinally thereof as well as rotation with respect to body 14. It is held centered within the body 14 by a plurality of outwardly extending pins 72 and 74 and the extent of reciprocable movement of the restrictor 68 is limited by rearwardly extending pin 76 engageable with plug 20 as well as by forwardly extending pin 78 engageable with head 30.

Any suitable means may be provided for moving the plunger 54 inwardly and thereby opening the valve 62

with respect to its seat 64. There is illustrated a solenoid 80 having a reciprocable core 82 for swinging an arm 84 that pivotally interconnects the core 82 and any stationary part 86 of the machine. It is seen that when the solenoid 80 is energized to retract its core 82, the arm 84 is swung inwardly to in turn exert inward force on the plunger 54 to open valve 62.

In operation, by virtue of the elongated annular passage 88 presented between restrictor 68 and the inner face of valve body 14, the pressure of the beverage emanating from the container 10 is reduced sufficiently prior to discharge past the valve 62 that the same is dispensed at relatively low velocities when the valve 62 is moved to the open position.

Pins 76 and 78 limit the extent of reciprocable movement of the restrictor 68 under influence of movement of piston 60 and the pressure of incoming liquid. Manifestly, the clearance 88 between restrictor 68 and the valve body 14 should be closely controlled to provide the required restriction to flow and resulting pressure drop. In order to handle various beverages requiring different inlet pressures and corresponding differences in pressure drops, restrictors 68 having different opposite outside diameters may be substituted for the restrictor 68 shown in the drawing. The beverage at a reduced pressure and velocity is discharged through the spigot 44 whenever the valve 62 is open.

Sudden displacement of the valve 62 from its normal position bearing against seat 64 is prevented by the dampening effect upon the piston 60 as the same moves into the sealed air chamber 66. This eliminates, therefore, to a considerable extent the agitation that would otherwise cause undue foaming of the beverage upon actuation of the plunger 54.

Attention is called to the fact that the valve is made in a manner to facilitate cleaning, since it is but necessary to remove the retainer 36 in order to permit removal of head 30, plunger 54 and restrictor 68. By the same token, the spigot 44 may be quickly and easily interchanged by retracting the retainer 46 against the action of spring 52.

Having thus described the invention, what is claimed as new and desired to be secured by Letters Patent is:

1. Valve structure of the kind described comprising: an elongated tubular body having an opening at one end thereof, an inlet orifice at the other end thereof and an outlet orifice intermediate the ends thereof and ad-

jacent said one end thereof; means presenting an annular valve seat between the inlet orifice and the outlet orifice and adjacent the latter; a plunger reciprocably mounted in the body and extending through said opening and said seat presenting means; valve means on the plunger between the inlet orifice and the seat presenting means and cooperable with the latter; an elongated restrictor having an imperforate end, an imperforate, generally cylindrical side wall and an opposite end provided with a cylindrical cavity presenting an air chamber; means mounting the restrictor within the body for free reciprocatory movement relative to the latter with said imperforate end of the restrictor facing the inlet orifice, said opposite end facing the seat presenting means, and said side wall spaced inwardly from the body presenting a fluid passage of annular cross section between the body and the restrictor throughout the length of the latter; means limiting reciprocation of the restrictor within the body between extreme positions in which the ends of the restrictor are spaced from both the inlet orifice and the seat presenting means but by differing distances in the two positions; and a piston on the inner extremity of the plunger reciprocably received within the air chamber of the restrictor in substantially fluid-tight relationship to the side wall of the restrictor and in spaced relationship to the imperforate end of the latter.

2. Valve structure as set forth in claim 1, wherein said body is comprised of a generally cylindrical tube; a head removably mounted in one end of the tube in fluid-tight relationship to the latter and provided with a longitudinal bore presenting said opening and said seat, and a lateral passage communicating with the bore and presenting said outlet orifice; and a plug removably mounted in the other end of the tube in fluid-tight relationship to the latter and provided with a longitudinal passage presenting said inlet orifice.
